(57) **CLAIM**

We claim the ornamental design for an inhaler, as shown and described.

DESCRIPTION

FIG. 1 is a perspective view of the inhaler.

FIG. 2 is a front elevation view of the inhaler.

FIG. 3 is a rear elevation view of the inhaler.

FIG. 4 is a right side elevation view of the inhaler.

FIG. 5 is a left side elevation view of the inhaler.

FIG. 6 is a top plan view of the inhaler.

FIG. 7 is a bottom plan view of the inhaler.

FIG. 8 is a front elevation view of the inhaler in a first open configuration; and,

FIG. 9 is a front elevation view of the inhaler in a second open configuration.

The dot-dash broken lines in FIGS. 8 and 9 showing portions of the internal structure of the inhaler in broken line form no part of the claimed design.

The dashed broken lines in FIGS. 8 and 9 showing portions of the internal structure of the inhaler in broken line form no part of the claimed design.

1 Claim, 9 Drawing Sheets
